(57) **CLAIM**

The ornamental design for tabs on a personal respiratory protection device, as shown and described.

DESCRIPTION

FIG. 1 is a perspective view of tabs on a personal respiratory protection device showing the new design.

FIG. 2 is a front elevational view thereof.

FIG. 3 is a rear elevational view thereof.

FIG. 4 is a top elevational view thereof; the bottom elevational view being a mirror image of the top view; and, FIG. 5 is a right elevational view thereof; the left side being a mirror image of the right side.

The broken line showing is for illustrative purposes only; it forms no part of the claimed design. The shading is provided only to show contour.
